UNITED STATES PATENT OFFICE.

JAMES DOWSON JACKSON, OF SYDNEY, NEW SOUTH WALES, AUSTRALIA.

OVEN PRINCIPALLY FOR DOMESTIC PURPOSES.

1,314,520.

Specification of Letters Patent.

Patented Sept. 2, 1919.

Application filed September 23, 1915. Serial No. 52,231.

To all whom it may concern:

Be it known that I, JAMES DOWSON JACKSON, of 197 Hay street, Sydney, in the State of New South Wales, Commonwealth of Australia, master plumber, have invented certain new and useful Improvements in Ovens Principally for Domestic Purposes, of which the following is a specification.

The present invention refers to ovens of the type having an isolated or non-contact heating chamber and has been specially devised to effect an improved oven of that type in which the disposition and arrangement of the flue passages the fire box and the outlet from said passages is so contrived that uniform heat distribution is effected about the heating chamber with economical heat consumption and moreover an oven of cheap and simple construction is also attained.

According to this invention the improved oven comprises essentially an isolated heating chamber surrounded by a bifurcated flue passage proceeding from a fire box positioned centrally below and from the front to the rear of said chamber to a common outlet disposed parallelly above and in the same vertical plane as the fire box. The outer wall of said flue passage is contained within the outer casing or shell of the oven and is preferably insulated from the same.

The said flue passage may be and is preferably vertically partitioned to form a plurality of passages all of which lead from the said fire box and communicate at the top with the flue outlet which box and outlet are common to all the flue passages. The vertical partitioning stated may progress in staggered formation to secure greater heating surface and effect baffling of the heat passing therethrough.

In the preferred form and for best results the two members forming the bifurcated flue passage have a corresponding cross sectional area and the mouth of the fire box and of the entrance orifice to the flue exit have each a cross sectional area equal to the combined similar area of the said members.

To eliminate any excessive draft influence upon the bifurcated flue passage the chimney or other leading out flue of the oven at its point of communication with the oven flue is also in communication with the air.

In the drawing—

Figure 1 is perspective view of a complete domestic cooking oven.

Fig. 2 is a vertical section on plane 2—2 of Fig. 1.

Fig. 3 is perspective view of a portion of the flue arrangement.

The heating or cooking chamber 8 of rectangular cross section extends practically the full depth of the oven outer casing 9 from the rear to the front walls of the latter and is isolated from the side and back walls of said casing 9 to provide the vertical and horizontal flue passages 13 and 14 respectively (see Fig. 2).

The outer wall 15 of these flue passages 13 and 14, which wall 15 is formed around all sides excepting the front of the chamber 8, is isolated from the side and rear walls of the oven casing 9 by insulation 17 of suitable material such as asbestos contained within chambers formed between the wall 15 and the outer casing 9.

This outer wall 15 of the flue passages 13 and 14 is so fitted that said passages are of equal cross sectional area throughout and constitute a bifurcated flue passage about the chamber 8 as shown in Fig. 2 both members of the bifurcation (each member consisting of one of the vertical passages 13 and the adjoining half sections of the top and bottom horizontal flue passages 14) being of equal length and area and proceeding from a common fire box 20 at the junction of the bifurcation to a common flue exit 21 disposed parallel to and in a vertical plane above the fire box 20 (see Fig. 2).

The cross sectional area of the mouth of the fire box 20 and of the flue exit 21 are equal and the area of each of said mouths is equal to the combined cross sectional area of the vertical passages 13.

It is essential to provide in an oven, the disposition and length of the flue passages 13 and 14 the arrangement of the fire box 20 and flue exit 21 and the cross sectional area of the same as described in order to secure the maximum result from this invention, the exact structural arrangements illustrated and described herein not being essential as same may be varied in design.

The vertical walls of the fire box 20 are formed by vertical terminations 22 of the outer wall 15 of the flue passages 13 and 14. The heating element consists of the pipe or tubular gas burner 23 of any approved form parallelly and centrally disposed between the walls 22 of the fire box 20 so that the flame from the burner is disposed in the

central vertical plane (3—3 Fig. 1) of the chamber 8. The end of the pipe burner 23 forward or adjacent to the oven door 4 is closed, while its rear end is connected 5 through the usual air mixing chamber 25 to the pipe 26 the supply to which latter is controlled in any known manner as by the valve 27 communicating with the oven main supply pipe 28.

10 The usual domestic oven fittings are shown applied to the construction illustrated and consist of the chamber 29 for warming plates or for like purpose disposed above the chamber 8 and its flue exit 21, with the 15 gas rings 30 and the grid top 31 which rings communicate with the main supply pipe 28 in the ordinary manner, such exterior fittings not forming part of this invention and being shown merely to depict a cooking oven 20 which while embodying this invention is complete with existing forms of fittings.

The heat deflector plate 32 (see Fig. 2) is removably attached to the bottom of the chamber 8 between the rails 33 and disposed 25 in the vertical central line of the fire box 20.

The mouth of the flue exit 21 communicates with the main flue 34 through the damper controlled pipe 35 said flue 34 at its point of communication with the pipe 35 30 being also in communication with the atmosphere to prevent excessive draw or draft influence upon the oven flue passages 13 and 14.

The oven described is used with the flue 35 passages about the chamber 8 of equal length and area and the mouth of the flue exit 21 and of the fire box 20 both of equal area and the latter an area equivalent to the combined passages forming the bifurcated flue as previously specified; the heat 40 applied from the common and centrally disposed fire box 20 uniformly distributes through the flue passages 13, the draft of

the oven having an equal effect upon each member of the bifurcated passage.

When the oven chamber 8 is of large dimensions any tendency for the heat to travel diagonally to the main flue pipe 34 is counteracted by vertically dividing or partitioning the flue passages 13 and 14 as shown in Fig. 3, these vertical divisions not being shown in Fig. 1 for the sake of clearness, and the plurality of flue passages 13 and 14 so formed may have lugs 37 alternately projecting from opposite partition surfaces.

What I claim and desire to secure by Letters Patent is:

In an oven, the combination of an isolated heating chamber extending the entire length of the oven, flue passages coextensive with said heating chamber and extending along the bottom wall, the side walls and the top of said heating chamber, a fire box extending the entire length of the oven and disposed centrally below the heating chamber and in a space forming the continuation of said flue passages, a vent chamber located centrally above the heating chamber and in a common vertical plane with the fire box, the cross-sectional areas of the mouth of the fire box and of the mouth of the vent chamber being equal to the combined cross-sectional areas of said flue passages, said flue passages terminating in said vent chamber, vertical partitions subdividing said flue passages in a plurality of compartments so as to prevent diagonal travel of the combustion gases, and staggered projections on the vertical partition walls to provide circuitous paths for the products of combustion.

In testimony whereof I affix my signature in presence of two witnesses.

JAMES DOWSON JACKSON.

Witnesses:

WALTER SIGMOND,

J. PARKER.
